UNITED STATES PATENT OFFICE

107,386

DESIGN FOR A DRESS

Alice Engel, New York, N. Y.

Application November 11, 1937, Serial No. 72,803

Term of patent 3½ years

To all whom it may concern:

Be it known that I, Alice Engel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the particular arrangement of the rhinestone embroidery on the jacket portion, as shown.

I claim:

The ornamental design for a dress, substantially as shown and described.

ALICE ENGEL.
